SHACKLE SEAL

Antonio di Palma, Pueblo, Colo., assignor, by direct and mesne assignments, of one-half to Raffaele Perrotta

Application March 8, 1948, Serial No. 13,640

2 Claims. (Cl. 292—307)

1

This invention relates to an improved shackle seal for box cars, meters, coin receivers, and the like.

In many devices of the present character, it is necessary, in order to secure the free end of the shackle wire in the metal pellet employed, to mash or otherwise mutilate said pellet. Such procedure has certain disadvantages, the most objectionable of which, perhaps, is the fact that the free end of the shackle wire is not always securely anchored.

The present invention therefore has as its objects to provide a seal wherein the free end of the shackle wire may, without the necessity of mutilating the head employed, be securely tied in the head, wherein the free end of said wire, once tied in the head, may not be untied without mutilating the head or cutting the wire, and wherein the head will, on the one hand, be formed to facilitate the tying of the free end of the shackle wire therein, and, on the other hand, will also be formed to lock the free end of said wire tied, so that the intermediate portion of the wire may not be pulled forwardly to release the wire while, also, the terminal free end portion of the wire may not be pushed backwardly out of the head to free the wire.

Other and incidental objects of the invention will appear during the course of the following description, and in the drawings:

Figure 1 is a front elevation of the head of my improved seal, the cover plate employed being removed.

Figure 2 is an edge elevation of the device, the cover plate being omitted.

Figure 3 is a vertical section on the line 3—3 of Figure 1, the cover plate being in place.

Figure 4 is a vertical section on the line 4—4 of Figure 1, the cover plate being in place.

Figures 5, 6, and 7 are more or less diagrammatic plan views showing how the free end of the shackle wire is tied in the head, the cover plate being omitted.

Figure 8 is a perspective view particularly showing the head and cover plate.

Figure 9 is a perspective view showing the seal in use.

In carrying the invention into effect, I employ a head, indicated as a whole at 10. The head is preferably circular, as a head of such shape has been found the most economical to manufacture. However, I do not wish to be limited in this respect, as the head may be of other configuration.

The head 10 comprises a base 11, and a cover

2

plate 12, both now to be described in detail. Both may be of compressible metal, as is well known in the art, or some soft alloy, but this feature is not imperative, and the base and cover plate may be of hard metal, or plastic, if so desired.

At one end, the base 11, as particularly seen in Figure 8, is formed with a recess 13 which defines a surrounding flange 14 within which the cover plate 12 normally fits snugly. The recess 13 has a flat floor 15. Formed in the floor of the recess is a socket 16, from which leads a slot 17 emerging through the periphery of the base.

The base 11 is further provided with a chordal slot 18, intersecting which is a diametric slot 19, so that the two slots are crossed to define what may be described as short ends above their intersection, as seen in Figure 1, and long ends below their intersection. As seen in Figure 3, the slot 18 is much deeper than the slot 19. Therefore, as between the two slots, the slot 18 may be designated as the deep slot, and the slot 19 as the shallow slot.

It is now to be noted that between the long ends of the slots 18 and 19, the peripheral wall 21 of the base 11 as well as the floor 15 of the recess 13 is cut away to provide a clearance space, designated in Figure 4 at 20. In thus cutting away the floor, a triangular boss 21 is defined, the upper surface of which is lower than the floor but higher than the bottom of either of the slots 18 or 19. This boss therefore forms an island between the long ends of said slots. At its outer periphery, the boss is beveled, as indicated at 22, and formed in the apex portion of said boss is a circular socket 23 providing a shoulder 24. Rising eccentrically from said socket near the upper portion of the rim thereof is a post 25 suitably fixed in the base 11.

Fixed at one end in the socket 16 of the base 11 to extend through the slot 17 is a shackle wire 26. The cover plate 12 is applied over the fixed end of said wire, and may be irremovably secured in position by indenting the flange 14, upsetting said flange, or other approved manner. The wire 26 is flexibly resilient, but, preferably, somewhat hard and somewhat resistant to bending in the fingers of the hand.

As will now be appreciated, the device is supplied, commercially, with the head 10 fixed to one end of the shackle wire 26, and in Figure 9 of the drawings, I have shown a typical use of the device, conventional ears to be sealed being indicated at 27.

To tie the shackle wire 26 in the head 10, the free end portion of the wire is, as shown in Fig-

ure 5, first inserted through the deep slot 18, after which the wire is bent to form a loop 28, when the free end of the wire is, as shown in Figure 6, inserted through the shallow slot 19 to cross over the portion of the wire lying in the slot 18. The purpose of the deep and shallow slots thus becomes clear. The deep slot 18 is of a depth to accommodate the diameter of the wire, so that when the free end of the wire is inserted through the slot 19, said end of the wire will easily ride over the portion of the wire in the slot 18.

After the wire 26 is looped through the slots 18 and 19, as shown in Figure 6, the free end of the wire is then pulled taught and tight, as shown in Figure 7. Looking at the loop 28 of the wire, as shown in Figure 6, it will be seen that, as the terminal end of the wire is pulled, said loop will ride up and over the beveled face 22 of the boss 21 to enter the clearance space 20, after which, as said loop grows smaller it will ride across said boss to enter the socket 23 in engagement about the post 25. Thus, as shown in Figure 7, it is then only necessary to pull the loop 28 tight about said post, when the loop will seat in said socket. In this connection, it is to be noted that the portion of the wire 26 in the slot 19 is confined by the plate 12 to closely overlie the portion of the wire in the slot 18, and since said portions of the wire cross each other close by the post 25, the portion of the wire in the slot 19, because of its resiliency will, when the loop 28 is contracted sufficiently to be received in the socket 23, force the loop into said socket to seat therein and thereafter prevent the loop from riding up the post out of said socket.

Assuming now that the shackle wire 26 is tied in the head 10, as previously described, it will be seen that, as shown in Figure 7, the intermediate portion of the wire may not, since the wire has been bent into a tight loop about the post 25, be pushed backwards. The shoulder 24 of the socket 23 would prevent any such procedure, while, should the terminal end of the wire be pulled, the loop 28 would only lock the tighter about the post. Rising of the loop over the post is prevented by the cover plate 12. Thus, the anchoring of the free end of the shackle wire may be accomplished without mashing the head 10, or without the aid of any special tools whatever.

Having thus described my invention, I claim:

1. A shackle seal including a head comprising a base and cover plate therefor irremovably se-

cured to the base, a shackle wire secured at one end to the base, the base being formed beneath said plate with intersecting slots crossed near corresponding ends thereof to define long ends and short ends, one of said slots being deeper than the other whereby the free end portion of the wire may be first inserted between the base and plate through the deep slot and then returned through the shallow slot over the portion of the wire lying in the deep slot to form a loop anchored near the apex between the long ends of said slots, and a post fixed beneath said plate to the base near said apex about which said post the loop may bind, the base being formed about said post with a socket to accommodate the loop tightened about the post and providing an adjacent shoulder adapted to block expansion of said loop.

2. A shackle seal including a head comprising a base and cover plate therefor irremovably secured to the base, a shackle wire secured at one end to the base, said base having a recess therein beneath said plate and being formed in the floor of said recess with intersecting slots one deeper than the other and crossed near corresponding ends thereof to define long ends and short ends and said floor being cut away between the long ends of said slots to provide a clearance space to accommodate the movement of a loop of the free end portion of said wire between the long ends of the slots toward the apex therebetween, and a post fixed beneath said plate to the base between the long ends of the slots near said apex, the base being provided with a socket about said post, whereby the free end of the wire may be first inserted between the base and plate through the deeper of said slots and then returned through the more shallow of said slots over the portion of the wire lying in said deeper slot to provide a loop movable through said clearance space into said socket tightened about said post.
